UNITED STATES PATENT OFFICE.

FREDRICK M. HAMILTON, OF DAYTON, OHIO.

PIPE-WRENCH.

1,379,978.

Specification of Letters Patent. Patented May 31, 1921.

Application filed June 26, 1919, Serial No. 306,810. Renewed April 15, 1921. Serial No. 461,681.

To all whom it may concern:

Be it known that FREDRICK M. HAMILTON, a citizen of the United States, residing at Dayton, in the county of Montgomery and State of Ohio, has invented certain new and useful Improvements in Pipe-Wrenches, of which the following is a specification.

This invention relates to new and useful improvements in pipe wrenches.

10 The object of the said invention is to provide a wrench which has certain specific structural features hereinafter described and claimed.

15 The accompanying drawings illustrate my improved wrench and reference thereto is now made in general terms preceding a more particular description to follow.

Figure 1 is a plan view of the improved wrench.

20 Fig. 2 is a side elevation of the same.

Fig. 3 is a plan view of a somewhat modified form of the wrench. Fig. 4 is a side elevation of the construction shown in Fig. 3. Fig. 5 is a section on the line 5-5 of Figs. 1 and 3.

Fig. 6 is a section on the line 6-6 of Fig. 1, and

Fig. 7 is a section on the line 7-7 of Fig. 3.

30 In the description to follow and in the drawings, similar reference characters indicate the same parts.

Referring in more particular terms to the said drawings, 1 represents the shank or main handle portion of the wrench which is provided with an extension —2— forming one of the jaws of the wrench, to wit, the fixed jaw. The said fixed jaw —2— is provided with a roughened or serrated surface —3— which effectually grips the pipe held thereby. The points of the teeth or serrations —3— it will be observed point inwardly to more properly engage the surface of the pipe held between the jaws.

40 The handle portion —1— of the fixed jaw is provided with side grooves —4— which form guides for the handle portion —5— of the movable jaw —8—. A shank —6— extends from the said handle portion —5— and the end of the said shank portion terminates in the movable jaw —8—. The said shank —6— is essentially of a resilient character owing to a portion thereof being

cut away on the side next to the shank —1— of the fixed jaw. By removing a portion of 55 the material in this manner a space is provided between the two shank portions —1— and —6— which permits the shank —6— to spring or flex inwardly when the two jaws grip between them a pipe and the 60 wrench is turned. The result is, the pipe so held is held with increasing force due to the movable jaw flexing inwardly on account of the elastic character of its supporting shank. The serrations of the fixed jaw 65 are thereby caused to more firmly engage the surface of the pipe. The movable jaw —8— in the present instance is provided with a similar roughened or serrated surface —9— although this is not wholly es- 70

75 The two jaws —2— and —8— are set at angles to permit them to properly grip the pipe and the resilient character of the movable jaw to force the pipe with added force. The said jaw —8— is moved relatively to the fixed jaw —2— by shifting the handle portion —5— along the guides —4— thereby permitting the said movable jaw to be 80 adjusted to any size pipe. In order to lock the said jaw —8— in any of its set positions the following means are provided. In Fig. 1 the handle portion —5— is provided with a limited number of ratchet 85 teeth —10— which are adapted to be engaged by a vertically sliding spring-controlled dog —11—. The said dog —11— is slidingly mounted in guides —12— cut in the sides of the handle portion —5—, 90 and the said dog is further provided with knurled sides to facilitate its ready disengagement from the ratchet teeth —10— to enable the adjustment of the movable jaw. This disengagement is effected by pressing 95 outwardly the dog —11— to free it from engagement with the teeth —10—. The said dog is forced out against the tension of a coil spring —5— the tendency of which is to maintain the engagement between the 100 said dog and the ratchet teeth —10—.

In Fig. 3 the handle portion —5— has mounted in it an eccentrically positioned knurled member —13— which is adapted to frictionally bind against the face of the 105 handle portion —1— of the wrench. The

said member —13— projects out of the handle portion —5— and may be rotated by the thumb to engage and disengage the handle portion —1—, thereby temporarily locking the movable jaw in any position to which it is set. The said movable jaw is permanently locked in position when the strain is thrown on the wrench in turning the pipe held therein, and at this time the 10 spring character of the said movable jaw becomes manifest by coming into play to add additional force on the pipe in its engagement with the fixed jaw. In the form shown in Fig. 3 the outer end of the resilient shank —6— near the jaw —8— is provided with one or two teeth —14— which are adapted to engage teeth —15— on the shank of the fixed jaw when the resilient shank —6— is flexed by the strain put upon 15 the wrench. The teeth —15— are located adjacent to the fixed jaw —2— on the handle portion —1— owing to the movable jaw having the greatest amount of movement at that point.

20 25 By thus mounting the movable jaw on a resilient shank or support the wrench is adapted to firmly and with increasing force

grip and securely hold the pipe during the turning thereof.

Having described my invention, I claim: 30

A pipe wrench having a handle portion with an extended shank terminated in a fixed jaw, the said handle portion having a longitudinal groove on each side thereof, a movable jaw member having a handle 35 portion having a shank portion, a portion of which extends over the sides of the handle portion of the fixed jaw member and is provided with guide ribs which extend into the grooves in the handle portion of the fixed 40 jaw member, whereby the movable jaw and handle are guided relatively to the fixed jaw and handle, the shank portion of said movable jaw being reduced in thickness from the handle portion thereof to the jaw to impart resiliency thereto and permit the movable jaw member to flex in the manipulation 45 of the wrench, and means in the handle portion of the movable jaw engaging the handle portion of the fixed jaw and holding said 50 parts in locked position.

In testimony whereof I affix my signature.

FREDRICK M. HAMILTON.
